CLAIM

The ornamental design for a package for cosmetic products, as shown and described.

DESCRIPTION

FIG. 1 is a perspective view of a package for cosmetic products showing a new design;

FIG. 2 is a front view of the new design;

FIG. 3 is a rear view of the new design;

FIG. 4 is a right side view of the design;

FIG. 5 is a left side view of the design;

FIG. 6 is a top view of the new design; and,

FIG. 7 is a bottom view of the new design.

Broken lines showing environmental elements form no part of the claimed design.
